Patented Mar. 12, 1918.

UNITED STATES PATENT OFFICE.

JOSEPH B. KASSER AND MORRIS KASSER, OF SAN FRANCISCO, CALIFORNIA.

LIFE-PRESERVER.

1,259,106.

Specification of Letters Patent. Patented Mar. 12, 1918.

Application filed December 18, 1916. Serial No. 138,110.

To all whom it may concern:

Be it known that we, JOSEPH B. KASSER and MORRIS KASSER, citizens of the United States, residing in the city and county of San Francisco and State of California, have jointly invented a new and useful Improvement in Life-Preservers, of which the following is a specification.

Our invention relates to improvements in life preservers or belts wherein distended chambers are formed between layers of elastic water-proof material to provide a buoyant member; and the objects of our invention are—

15 First, to provide an improved life preserver or belt that may be worn with comfort in conjunction with the night clothing;

Second, to provide an improved life preserver or belt that is normally sufficiently inflated to support a person on the surface of a body of water;

Third, to provide an improved life preserver having two independent sets of chambers, one set of which is normally inflated to a sufficient extent to support a person, the other set of chambers being adapted to be easily and quickly inflated to increase the buoyancy of the device.

30 We accomplish these several objects by means of the device disclosed in the drawings forming a part of the present specification, wherein like characters of reference are used to designate similar parts throughout the said specification and drawings, and in which—

Figure 1 is a broken elevation of one side of our improved life preserver disclosing the normally distended side;

40 Fig. 2 is a sectional view taken on line X—X of Fig. 1 in the direction indicated by the arrows;

Fig. 3 is a perspective view of the device formed in the position assumed when attached or secured to the person;

Figs. 4 and 5 are enlarged sectional views taken on line Z—Z of Fig. 4 disclosing the valve in closed and opened positions respectively.

50 Referring to the drawings, the numeral 1 is used to designate a life preserver comprising a belt formed of three layers of elastic water-proof material 2, 3 and 4. One outer layer 2 has a plurality of vertically disposed distended chambers 6 formed therein and apertured at the lower ends

thereof as at 7 the purpose of which apertures will hereinafter be more fully set forth.

These portions of the outer layer 2 that lie between the distended chambers 6 are secured to the central layer 3 by means of a suitable cement, vulcanizing or other suitable method.

The other outer layer 4 is secured at regular intervals to the central layer 3 so as to form a set of vertically disposed chambers 8 all inter-connected by means of upper and lower horizontally disposed chambers or connections 9 as shown in perspective 70 in Fig. 3 of the drawings. The chambers 8 are held independent from the first set of chambers 6 by means of the central layer 3.

The chambers 6 are normally inflated by means of their distended construction or 75 formation, the apertures 7 readily permitting the entrance of the atmosphere. As these apertures 7 are located at the lower ends of the chambers 6 it is obvious that when the wearer enters the water said water 80 will effectively close said apertures against the egress of air therein.

This arrangement renders the belt normally buoyant to a sufficient degree to readily support a person upon the surface 85 of a body of water. Should additional or greater buoyancy be required the independent set of chambers 8 normally deflated, may be easily and readily inflated by means of a tube 11 connected therewith and provided at its upper end with a collapsible valve 12 the nature and construction of which is disclosed in Figs. 4 and 5 of the drawings. The said valve 12 consists of a rubber or other elastic insert or plug 14 95 split as at 16. The resilient nature of the plug or insert 14 normally retains the split 16 closed as in Fig. 4 of the drawings but by pressing the sides of the valve together the split is opened as disclosed in Fig. 5 100 of the drawings whereby the chambers may be either inflated or deflated.

The belt is provided with suitable leg straps 17 and suitable body straps 18 by means of which the belt 1 may be secured 105 to the body of the wearer.

The belt 1 being composed of soft, pliable, waterproof material may be easily worn without discomfort under the night clothing when aboard ships or other places where 110 there is any danger of drowning.

It is obvious from the foregoing that we

have provided an improved life preserver or belt adapted to be sufficiently inflated to sustain the person upon the surface of a body of water and also means whereby additional or greater buoyancy may be easily and readily imparted to the device.

It is also evident that the belt may be deflated and rolled within a comparatively small and compact package requiring little 10 room for storage when not in use.

The slip covers are provided to prevent the contact of the cold rubber belt with the body.

Having thus described our invention what 15 we claim as new and desire to secure by Letters Patent is—

1. A life preserver comprising a belt formed of three layers of elastic water-proof material, one outer layer having a plurality of distended chambers formed therein and open to the atmosphere on the lower ends thereof, the other outer layer being secured at intervals to the center layer to form a plurality of closed chambers.

2. A life preserver comprising a belt formed of three layers of elastic water-proof material, one outer layer having a plurality of distended chambers formed therein and open to the atmosphere on the lower ends thereof, the other outer layer being secured at intervals to the center layer to form a plurality of closed chambers; and means for inflating the second mentioned chambers.

3. A life preserver comprising a belt formed of three layers of elastic water-proof material arranged in parallel relation, one

outer layer having a plurality of distended chambers formed therein open to the atmosphere at the bottom, the other outer layer being secured at intervals to the central layer to form a plurality of closed inter-connected chambers; an inflated tube connected to the second mentioned chambers; and a suitable valve connected to the end of the tube to retain the inflation of the 40 45 said inter-connected chambers.

4. A life preserver comprising a belt formed of three layers of elastic water-proof material, one outer layer having a plurality of distended chambers formed therein 50 and open to the atmosphere at the lower ends thereof, the other outer layer being secured at intervals to the central layer to form a plurality of closed chambers; means for inflating the second mentioned chambers; and means for securing the belt to the person.

5. A life preserver comprising a belt formed of three layers of elastic water-proof material, one outer layer having a plurality of distended chambers formed therein 60 and open to the atmosphere on the lower ends thereof, the other outer layer being secured at intervals to the central layer to form a plurality of closed chambers; means for inflating the second mentioned chambers; and suitable straps to connect the belt to the person.

In witness whereof we have hereunto set our signatures.

JOSEPH B. KASSER.
MORRIS KASSER.
